Primary Examiner — Patricia A Palasik*(74) Attorney, Agent, or Firm* — McAndrews, Held & Malloy, Ltd.**CLAIM**

The ornamental design for a 3D printer hotend, as shown and described.

DESCRIPTION

FIG. 1 is a front-top perspective view of a 3D printer hotend showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a rear-bottom perspective view thereof.

The dashed broken lines in the figures illustrate portions of the 3D printer hotend that form no part of the claimed design.

1 Claim, 8 Drawing Sheets(56)
